GEORGE VAN DYKE, OF NEW BRUNSWICK, NEW JERSEY.

VACUUM RADIATOR-VALVE.

1,085,885.

Specification of Letters Patent.

Patented Feb. 3, 1914.

Application filed April 30, 1912. Serial No. 694,219.

To all whom it may concern:

Be it known that I, GEORGE VAN DYKE, a citizen of the United States, residing at New Brunswick, in the county of Middlesex and State of New Jersey, have invented 5 a new and useful Vacuum Radiator-Valve, of which the following is a specification.

This invention has reference to improvements in valves for steam radiators and its 10 object is to provide a means for clearing pocketed air from the radiators so that there may be established quickly a circulation of steam in the radiators.

In accordance with the present invention, 15 there is provided a nipple ending in a nozzle which nipple may be tapped into the inlet pipe of the radiator and connected to the other end of the radiator by a suitable pipe in such manner that the inrushing steam 20 will create vacuum conditions at the nozzle to cause air lodged at the other end of the radiator to flow through the nozzle into the steam supply pipe, whereby the trapped air is removed and the proper circulation may 25 be set up.

The invention will be best understood from a consideration of the following detailed description taken in connection with the accompanying drawings forming a part 30 of this specification, with the further understanding that while the drawings show a practical embodiment of the invention, it is susceptible of other practical embodiments wherefore the invention is not confined to any strict conformity with the showing of the drawings, but may be changed and modified so long as such changes do not mark any material departure from the salient features of the invention.

40 In the drawings:—Figure 1 is an elevation of a radiator with the invention applied; Fig. 2 is a plan view of the structure shown in Fig. 1; Fig. 3 is a longitudinal diametrical section with parts in elevation 45 and drawn to a larger scale, of the valve structure. Fig. 4 is a section on the line 4—4 of Fig. 3.

Referring to the drawings, there is shown a radiator 1, indicated as made up of a plurality of connected sections which may be taken as typical of any suitable radiator structure. At one end, the radiator is shown as provided with a supply pipe 2, including the usual controlling valve 3, and it 55 may be assumed that the radiator system is of that type wherein the supply pipe con-

stitutes the return pipe for steam and water of condensation.

It is usual to provide radiators at the end remote from the inlet with a relief valve, 60 commonly known as an air valve. In accordance with the present invention, a small pipe 4 is connected to that end section of the radiator remote from the pipe 2, at about the place usually occupied by the air valve, 65 and when the invention is applied to existing radiators, the pipe 4 may be connected to the radiator at the same opening designed for the air valve. Since the majority of radiators are of the two or more column 70 type, the pipe 4 is carried through the radiator sections between the columns, the continuity of the pipe being broken by bends or elbows wherever necessary.

Applied to the pipe 2, is a nipple valve 75 structure 5, having at one end an exteriorly-threaded radial flange 6, for the application of a union coupling 7^a, connecting the member 5 with the pipe 4. The body of the member 5 remote from the flange 6, is formed 80 with a nozzle extension 7, having an intermediate portion 8 screw-threaded to engage in a suitable screw-threaded hole formed at an appropriate point through the wall of the steam pipe 2, between the valve 3 and 85 the radiator. The body 5 is formed with an axial bore 9, communicating with another axial bore 10 of smaller diameter extending through the nozzle 7, and the extremity of the nozzle 7 has its outer walls 90 tapered toward the bore, as indicated at 11. On one side of the body portion, there is formed a boss 12, into which there is tapped a passage 13, terminating in a valve seat 14, communicating by way of a smaller passage 95 15 with the bore 9 near that end of the latter which communicates with the bore 10. Adapted to the passage 13, is the threaded stem of a screw 16 terminating at one end in a valve 17 shaped to the seat 14 and at 100 the other end provided with a head 18 which may be milled for convenience of manipulation. Extending from the passage 13 is another passage 19 to the exterior of the boss 12, and so located that it may be controlled by the screw 16. When the invention is installed, the valve member 5 is substantially upright with the end of the nozzle shown at 11 extending for a short distance into the pipe 2 in a direction transverse to 110 that of the flow of steam therethrough.

Let it be assumed that the valves 3 and 17

are closed, and that it is desirable to cause the introduction of steam into the radiator. The valve 3 is opened and steam enters the radiator through the pipe 2. The stream of steam traversing the open end of the nozzle 7 tends to withdraw air therefrom, thus setting up vacuum conditions within the bore 10 and through the latter within the bore 5 and pipe 4, and causing a flow of air from 10 the further end of the radiator to and through the bore 10 of the nozzle 7. Any air therefore, which may be pocketed in the remoter portion of the radiator, is withdrawn therefrom and the incoming steam 15 finds ready access to all parts of the radiator since its flow is not obstructed by dead bodies of air. As the radiator gets filled with steam, there is condensation and the water of condensation will in part flow 20 through the pipe 4 into the bore 9, filling the latter, thus preventing live steam from passing through the valve structure 5, into the pipe 4 and thus to the further end of the radiator. When it is desired, the water 25 thus lodged in the pipe 4 and bore or chamber 9, may be readily withdrawn by manipulating the screw 16, to place the passages 15 and 19 in communication and the water will readily gravitate to and through the passage 19.

The present invention is advantageous over other devices for a like purpose in that it has no stop valves, balance valves, floats or expansion valves, and, moreover, it is entirely automatic in action.

What is claimed is:—

1. A steam radiator provided with a steam inlet pipe, an air pipe leading from the end of the radiator remote from the steam pipe 40 to said steam pipe, and a nipple device consisting of a body portion having one end connected to that end of the air pipe adjacent the steam pipe and at the other end formed into a nozzle extension with its exterior provided with screw threads and there screwed into the steam pipe in transverse relation to the passage of steam therethrough, the nipple device having an unimpeded through passage from end to end and up 50 right in operative position with the open end of the nipple elevated above the lower inner surface of the steam pipe and above the bottom of the radiator.

2. A steam radiator provided with a steam inlet pipe, an air pipe connected at one end to that end of the radiator remote from the steam pipe, and a nipple device consisting of a body portion having a connection at one end with that end of the air pipe remote 60 from the end connected to the radiator, and the other end formed into a nozzle extension threaded at an intermediate point on said nozzle extension and screwed into the steam pipe and terminating within the steam pipe 65 at a distance above the bottom of the free

steam space through said steam pipe, said nipple device having an unimpeded through passage from end to end and also an intermediately located means for the drainage of said passage, the nipple device standing substantially upright when in operative position. 70

3. A steam radiator provided with a steam inlet pipe, an air pipe leading from that end of the body of the radiator remote from the steam pipe, and a nipple device comprising a body portion having a boss at one side and at one end provided with a nozzle extension with exterior screw threads screwed into the steam pipe with the discharge end of the nozzle within said steam pipe in transverse relation to and in the path of steam entering the radiator through the pipe, and the other end of said body portion being connected to the corresponding end of the air pipe, said body portion and nozzle having aligned longitudinal bores with the bore of the body portion larger than that of the nozzle and the boss being provided with a valved drain passage for the bore of the body portion where connecting with the bore of the nozzle. 80

4. A steam radiator provided with a steam inlet pipe, a nipple device having at one end a nipple extension screwed into the steam pipe with its discharge end in transverse relation to and in the path of steam passing through the pipe, said nipple device having a boss at one side exterior to the steam pipe and with longitudinal aligned bores, the boss having intersecting drain passages leading 95 from one of the bores exterior to the steam pipe, and provided with a valve screw movable along one of the intersecting passages into and out of closing relation to said passages, and an air pipe connecting with the 100 end of the nozzle device remote from that entering the steam pipe and leading to the end of the radiator remote from the steam pipe, said nipple device standing substantially upright when in operative position. 110

5. A steam radiator provided with a steam inlet pipe, an air pipe leading from the end of the radiator remote from the steam pipe, and a nipple device connecting the air pipe to the steam inlet pipe and comprising a body portion with a bore communicating at one end with the air pipe, and near the other end provided with a valved drain passage for said bore, and a nozzle continuation of the body portion having a bore of smaller and substantially constant diameter therethrough connecting with the end of the first-named bore remote from the air pipe, said nozzle extending and opening into the interior of the steam inlet pipe of the radiator 115 in a direction substantially perpendicular to the longitudinal axis thereof. 120

6. A steam radiator provided with a steam inlet pipe, a nipple device having a discharge portion entering the steam inlet pipe 130

in a substantially upright position and substantially perpendicular to the longitudinal axis of the steam pipe with the outlet of the nozzle within the line of travel of the steam passing through the pipe into the radiator, and an air pipe leading from the upper end of the nipple device to the end of the radiator remote from the steam inlet pipe and communicating with the radiator 10 at a high point thereof.

7. An attachment for steam radiators comprising a nipple structure having a body portion with means at one end for the attachment of a pipe thereto and at the other end provided with an extension of reduced diameter terminating in an exteriorly tapered end and provided with exterior screw threads between the tapered end and that portion of the extension where joining the 20 body portion, said nipple structure having an unimpeded passage longitudinally therethrough with that part of the passage located within the body portion of greater diameter than that portion located within 25 the nozzle extension, and said body part of the structure being provided with a valved drainage passage communicating with that

part of the longitudinal passage which is of the larger diameter.

8. An attachment for steam radiators 30 comprising a nipple structure having a body portion with means at one end for the attachment of a pipe thereto and at the other end constructed for insertion into the steam inlet pipe of a steam radiator, said nipple 35 structure having a free passage longitudinally therethrough with the portion within that part of the nipple structure for insertion into the steam inlet pipe of the radiator of less diameter than the remainder of the 40 passage, and said nipple structure being provided with a valved passage communicating with that part of the longitudinal passage which is of the larger diameter near its junction with that part which is of the smaller 45 diameter.

In testimony, that I claim the foregoing as my own, I have hereto affixed my signature in the presence of two witnesses.

GEORGE VAN DYKE.
